UNITED STATES PATENT OFFICE.

NICHOLAS FEINEN, OF BUFFALO, NEW YORK.

SNAP SWITCH.

Application filed June 25, 1921. Serial No. 480,413.

To all whom it may concern:

Be it known that I, NICHOLAS FEINEN, a citizen of the United States, residing at Buffalo, in the county of Erie, and State of New York, have invented new and useful Improvements in Snap Switches, of which the following is a specification.

This invention relates to improvements in electrical switches of the snap type in which the switch is opened and closed by rotating a handle member, the general object of the invention being to provide indicating means associated with the handle member for indicating the "off" and "on" positions of the switch.

Another object of the invention is to simplify the construction so that the switch can be manufactured to sell at low cost and to reduce the number of parts so that the switch will be of simple operation and not liable to get out of order.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of the invention.

Figure 2 is a central sectional view.

Figure 3 is a view showing certain parts of the switch unassembled.

In these views 1 indicates the insulated base of the switch and 2 the enclosing casing for the switch parts. The two contacts 3 are secured to the base by the screws 4 and these contacts include the usual binding screws for holding the terminal wires of the circuit.

An opening is formed in the center of the base 1 and a screw threaded sleeve 5 passes through said opening and through an opening in the casing. This sleeve is connected with the base by the nuts 6 which engage the top and bottom faces of the base. The spring switch blade 7 has a perforated cup-shaped central part which fits over the sleeve and a washer 9 on the sleeve has a forked ear 10 which engages a part of the blade. This washer is adjusted on the sleeve by the nut 11. A spring 13 is located in the cup-shaped part of the blade and bears against

the bottom of said cup-shaped part and the washer so that the blade is frictionally held against the contacts. A shaft 14 passes through the sleeve with its square lower end 60 engaging the square hole in a bracket 15 which is supported on the lower face of the base by the screws 4, thus the shaft 14 is held against rotary movement. A disc 16 is connected with the upper end of the shaft 65 and this disc carries suitable indicia 17, such as the words "on" and "off." A cap 18 fits over the disc and said cap is provided with an opening 19 through which the words on the disc will appear. A plug 20 of insulating material fits in the cap and is held therein by the screw 21. This plug includes a screw threaded bushing 22 which engages the upper end of the screw threaded sleeve and the lower end of which bears against 75 nut 17.

It will thus be seen that the switch blade can be moved by rotating the cap by the fingers as this movement of the cap will cause the sleeve and its attached parts to 80 move and the blade will be moved by its engagement with the forked ear 10 of the washer 9. As the disc 16 is held against rotary movement by reason of the fact that the shaft 14 has a square end engaging a 85 square hole in bracket 15, the words on said disc will appear through opening 19 as cap 18 is rotated. The drawings show the parts arranged to be moved a quarter turn to cause the switch blade to travel from "off" 90 position to "on" position and vice versa.

It is thought from the foregoing description that the advantages and novel features of my invention will be readily apparent.

I desire it to be understood that I may 95 make changes in the construction and in the combination and arrangement of the several parts, provided that such changes fall within the scope of the appended claims.

What I claim is:

1. A switch of the class described comprising a base, contacts thereon, a hollow member rotatably supported by the base, a switch blade connected with the hollow member and engaging the contacts, a cap member connected with the hollow member and having an opening therein, a stationary member passing through the hollow shaft and an indicator disc connected with the stationary member and located within the cap. 105

2. A switch of the class described comprising a base, contacts thereon, a hollow

100

110

screw threaded member rotatably supported by the base, a stationary shaft passing through the hollow member, said stationary shaft having a square end, a bracket secured to the base having a square hole therein receiving the square end, an indicator disc secured to the hollow member, a cap member having an opening therein enclosing the

disc, a plug connected with the cap member and having a part connected with the hollow member, a switch blade and means for connecting the same with the hollow member.

In testimony whereof I affix my signature.

NICHOLAS FEINEN.
